To all whom it may concern:

Be it known that I, ISAAC E. PALMER, of Middletown, in the county of Middlesex and State of Connecticut, have invented and produced a new and original Design for Hammocks, of which the following is a specification, reference being had to the accompanying drawing, forming a part thereof.

The leading feature of my design consists in a hammock the body of which is provided with a valance upon its opposite edges, embellished with a stripe in the form of a series of scallops.

A represents the central portion of the body of the hammock, *a a'* the valance upon its opposite sides, and B the scalloped stripe. Rosettes *b* are shown at the points where the scallops intersect.

What I claim is—
